WALL THERMOSTAT

Frederick M. Hill, Columbus, Ohio, assignor to
Ranco Incorporated, Columbus, Ohio

Filed Mar. 30, 1970, Ser. No. 22,097

Term of patent 14 years

Int. Cl. D10—07

U.S. Cl. D52—7

FIG.1

FIG.2

FIG.4

FIG.3

FIG.5

FIG. 1 is a top plan view of a wall thermostat embodying the new design;

FIG. 2 is a front elevation thereof;

FIG. 3 is a bottom plan thereof;

FIG. 4 is a side elevation thereof as seen from the right of FIG. 2; and

FIG. 5 is a sectional view taken substantially along line 5—5 of FIG. 2.

I claim:

The ornamental design for a wall thermostat, substantially as shown.
